(57) **CLAIM**

The ornamental design of a bottle, as shown and described.

DESCRIPTION

FIG. 1 is a front view of the bottle of our new design, the bottle body at the upper end of the bottle and the closed dispenser cap at the lower end of the bottle as viewed in FIG. 1.

FIG. 2 is a front-top perspective view of the bottle shown in FIG. 1 and showing the top end of the bottle body.

FIG. 3 is similar to FIG. 1 but with the dispenser cap removed from the bottle body, the dispenser cap open with the lid of the dispenser cap swung away from the base of the dispenser cap; and,

FIG. 4 is similar to FIG. 3 but with the dispenser cap closed. The broken lines in FIGS. 1 and 2 illustrates the environment in which the design is used and is not part of the claimed design

No color is claimed as part of the design.
